UNITED STATES PATENT OFFICE.

ANDREW J. CARMICHAEL AND JOHN R. PETERSON, OF NEW HAVEN, CONNECTICUT,
ASSIGNORS TO THE GREIST MANUFACTURING COMPANY, OF NEW HAVEN, CON-
NECTICUT, A CORPORATION OF CONNECTICUT.

LAMP-SHADE SUPPORT.

Application filed March 13, 1923. Serial No. 624,772.

To all whom it may concern:

Be it known that we, ANDREW J. CARMICHAEL and JOHN R. PETERSON, citizens of the United States of America, residing at 5 New Haven, in the county of New Haven and State of Connecticut, have invented a certain new and useful Improvement in Lamp-Shade Supports, of which the following is a full, clear, and exact description.

10 This invention relates to means for supporting lamp shades from lamps, such as the globes of electric lamps.

An important feature of the invention is comprised in a device of the character referred to which is constructed of sheet material and preferably of sheet metal, and embraces a pair of diametrically opposite lamp-engaging members which are connected with a shade, and have sufficient resiliency 15 to maintain engagement with the bulb of the lamp and at the same time to permit angular adjustment of the shade.

Another important feature of the invention consists in a lamp shade support of the character referred to in which the lamp engaging members terminate in circular clamping portions which are of sheet metal which is bent or distorted transversely of its plane circumferentially to provide a curved or 20 rounded surface for contact with the lamp bulb, thereby strengthening the clamping members and providing a finished surface on said members for engagement with the bulb.

Other features of the invention, such as 25 important details of construction and combinations of parts, will be best understood from the following description, and the novel elements will be pointed out in the appended claims.

40 In the drawings:

Fig. 1 represents a lamp shade in section, and the shade support in elevation, said shade support being in normal position on a bulb.

45 Fig. 2 is a side elevation of the support taken at right angles to Fig. 1, and

Fig. 3 is an inverted plan view of Fig. 2.

The shade supporting device comprises two members made of sheet material, such 50 as sheet metal. One of said members comprises a terminal flat portion 1, with a central perforation, a downwardly inclined arm 2 and a circular bulb-engaging part 4, and the other member comprises a terminal flat

portion 6 having a central perforation, a 55 downwardly inclined arm 3, and a terminal circular bulb-engaging portion 7. The flattened portions 1, 6 are arranged with their apertures in alignment and a clamping screw having a shank 8, and head 10 is passed 60 through the aligned perforations and other perforations in a washer 11 and the top central portion of the shade 12, said shank being received in a threaded socket of an ornamental knob 14, which cooperates with the 65 screw in firmly securing the several parts together.

Preferably, the circular bulb clamping parts 4, 7, are bent transversely of the planes in which they lie to form convexly curved 70 lamp-engaging ribs 15 which not only act to stiffen the members, but also provides a finished edge for engagement with the surface of the bulb B. When the parts of the shade support are assembled and clamped 75 to the shade, as shown in Fig. 1, it will be seen that the arms 2, 3 may extend outwardly and downwardly at an inclination and that the circular terminal portions likewise extend divergently, and engage the upper 80 globular surface of the bulb. The material of which the members of the clamp is composed is preferably resilient sheet metal and the arms have sufficient elasticity to maintain the circular portions in yielding 85 engagement with the opposite sides of the bulb or lamp.

If it be desired to adjust the shade angularly upon the bulb so as to obscure the light in any given direction to prevent the 90 glare from any particular side of the lamp, such adjustment may be easily made by tilting the shade, the elastic clamping members serving to hold the shade to the bulb, regardless of the position into which the shade 95 is tilted, within certain limits, but these limits are sufficient for all practical purposes.

While we have shown the support as composed of two members clamped together, it 100 is obvious that in some cases it might be desirable to form the arms 2, 3 and their terminal circular portions of a single piece of metal. These and other changes may be made in the details of the construction of 105 the parts, or in their arrangement without departing from the spirit of the invention, and the right is reserved to make such

changes as fall within the scope of the following claims.

What we claim and desire to secure by United States Letters Patent is:

- 5 1. A shade support comprising, in combination, a plurality of flat sheet metal arms arranged to extend divergently from a central point of connection with a lamp shade, said arms terminating in circular lamp-engaging portions, said circular portions being bent transversely of their planes to form convexly curved lamp-engaging surfaces.
- 10 2. A device of the class described, comprising, in combination, two arms of resilient sheet material arranged to extend divergently downward and terminating in circular lamp-engaging portions which are bent transversely of their planes to present curved lamp globe engaging surfaces, and
- 15 20 means for rigidly securing said members to the inside central portion of a lamp shade.

- 25 3. A device of the class described, comprising, in combination, two arms each having a terminal flattened portion provided with a perforation, and a downwardly extending outwardly inclined portion terminating in a circular lamp engaging portion, said members being of resilient sheet metal bent transversely of their planes to present rounded lamp globe engaging surfaces, means extending through the aligned perforations of said flattened portions and through a similar perforation in a lamp shade, and a clamping knob to engage said means and cooperate therewith to secure said members to the shade.

In testimony whereof we have hereunto set our hands this 15th day of February A. D. 1923.

ANDREW J. CARMICHAEL.
JOHN R. PETERSON.
